UNITED STATES PATENT OFFICE.

EDWARD L. DUNN, OF WORCESTER, MASSACHUSETTS, ASSIGNEE, BY MESNE ASSIGNMENTS, TO STANDARD FLYNGER ELEVATOR COMPANY, OF WORCESTER, MASSACHUSETTS, A CORPORATION OF MASSACHUSETTS.

AUTOMATIC ELEVATOR CONTROL.

1,156,987.

Specification of Letters Patent. Patented Oct. 19, 1915.

Application filed September 12, 1913. Serial No. 789,429.

To all whom it may concern:

Be it known that I, EDWARD L. DUNN, a citizen of the United States, residing at Worcester, in the county of Worcester and State of Massachusetts, have invented certain new and useful Improvements in Automatic Elevator Controls, of which the following is a full, clear, and exact specification.

10 This invention relates to automatic elevator controllers, and has particular reference to an improved floor indicator construction whereby the circuits and parts are considerably simplified, and also the adjustment of the indicator simplified for accurately effecting the floor stops.

The invention has reference generally to a type of automatic elevator heretofore invented by me, such as shown in Patent 2,098,744, dated March 21, 1911, wherein the actuation of a push button or starting switch causes the main switch to be closed to send the elevator in the desired direction to a predetermined floor, and automatically stop. 25 The starting of the machine sets a stop circuit, which is completed by an indicator traveling synchronously with the car, and acting to open the running circuits when the predetermined floor is reached and restore all the parts to normal position. In 30 this patent, the stop is electrically effected, but in many instances it is preferable to simplify the mechanism by permitting the motor to mechanically operate a stationary switch to stop the car. It is also desirable to provide a finer adjustment of the floor stops than is disclosed in the said patent, in order that the car will more accurately stop level with the floor when a circuit 35 corresponding thereto is opened.

By the construction herein described, the foregoing objects are attained, together with various other advantages which will more fully appear in connection with the description of the accompanying drawings wherein—

Figure 1 is a diagram of an elevator system embodying the invention, controlled for purposes of illustration by a full set of push buttons at each floor; Fig. 2 is a detail on an enlarged scale of the indicator; and Fig. 3 is a side elevation of Fig. 2, partly in section.

Referring first to Fig. 1, 1 represents a

motor, herein shown as of the alternating current type having its leads connected to a suitable main switch 2 provided with moving contacts 3¹, 4¹, 5¹ closing the corresponding stationary contacts to send the car down and opposite moving contacts 3², 4², 5² closing the corresponding stationary contacts to send the car up. These moving contacts are mounted on opposite ends of a rocking lever arm, which is caused to close the down contacts when a down magnet D is energized and the up contacts when an up magnet U is energized. The current is supplied from the lines through fuses f, f¹, f², and the motor circuits, so far as necessary to an understanding of this invention, can readily be traced through the motor switch contacts. The circuits other than the motor circuits are, first, a starting circuit, second, a maintaining circuit, and a branched circuit for the main switch magnet. The closing of a push button, or any other form of starting switch, will energize a floor magnet, which will close a switch and energize one of the main switch magnets D or U, depending upon the position of the indicator relatively to the push button which is operated, the indicator having a down side in circuit with magnet D and an up side in circuit with magnet U, these two sides being separated so that only one circuit at a time can be made. The maintaining circuit is also provided with a non-interference switch which is closed only when the main switch is open and opened by the closing of the main switch so that after one push button is operated, all of the others are cut out. Door switches are also provided so that the motor cannot be operated in case any well or car door is open.

The starting circuit is led from fuse f by wire 5 through non-interference switch 6, which, as above stated, is closed only when the main switch is open, thence in multiple to a series of bars 7, 7, 7, etc., one being at each floor and one also in the car, if desired. At each floor is a series of push buttons 8, 8, 8, etc., corresponding to the various floors and respectively in multiple with wires 9, 9, 9, etc., so that the operation of any push button 8 corresponding to a floor connects wire 5 with one of the wires 9. The latter are connected respectively with floor magnets corresponding to the several floors m¹,

$m^2, m^3, m^4, m^5, m^6, m^7$ which are all connected on the other side in multiple with a wire 10, which leads through door switches d in series, thence by wire 11 back to fuse f^1 . From fuse f^1 the maintaining circuit leads by wire 12 to contacts 13 of magnets m^1, m^2 , etc., which is bridged by armature 14 when the magnet is energized by a push button to contact 15 from which contacts 15, wires 16 lead to stationary switch contacts $s^1, s^2, s^3, s^4, s^5, s^6, s^7$, etc., there being one for each floor. Cooperating with these stationary contacts s^1 , etc., are movable contacts carried by levers 17 pivoted at 18 on a suitable base. The levers 17 in Fig. 1, in order to be shown diagrammatically, are turned in a 90° plane, their correct position being as shown in Figs. 2 and 3, wherein they swing toward and from a vertical plane. The movable contacts carried by the levers 17 are connected by wires 19 to brushes b^1, b^2, b^3 , etc., which bear on the periphery of two direction segments SD, SU, which are insulated from each other and mounted on a slate base B' which is rotated in synchronism with the elevator by a shaft S. As shown in Fig. 1, the brush b^4 is resting on the insulation between segments SD and SU showing switch s^4 open and consequently the elevator is stopped at the fourth floor. The brushes b^1, b^2, b^3 are therefore in contact with segment SD and the remaining brushes, other than b^4 , are in contact with segment SU. It will therefore be seen that when a push-button corresponding to floor 2 is pushed, magnet m^2 will be energized and a current sent through armature 14 and wire 16, switch s^2 to brush b^2 , thence through the segment SD to brush b^1 , thence by wire 21 through magnet D and wire 22 to fuse f^1 . If a button be operated corresponding to the floor where the car is already stopped, it will be seen that the starting circuit is not made, because the brush of that floor will be on the insulation between segments SD and SU, as is shown in the case of brush b^4 in Fig. 1. At the same time that magnet m^2 moved armature 14 to connect contacts 13, 15, it moved an armature 23 to connect contacts 24, 25, thereby supplying current from wire 16 through switch s^2 , wire 19, brush b^2 , wire 27 to contact 24, armature 23, contact 25 to wire 9 of magnet 2, thus maintaining magnet m^2 energized after the push-button has been released and also after non-interference switch 6 has opened. Should any door switch d be opened, however, magnet m^2 would be deenergized and also the main switch magnet and the car stopped.

With the position shown in the drawings, with the car stopped at the fourth floor, upon closing a push button for floor 2, magnet D will be energized and the car will go down and continue running until the switch s^2 is mechanically opened by the indicator. These switches s^1 , etc., are successively opened as the indicator passes, but it will be observed that only one of these switches (the one corresponding to the destination floor) will be alive, and the car stops when this live switch is opened. These switches of course open before the car is actually at the floor, so that when the car actually stops, the brush, as b^4 , will rest on the insulation between segments SD and SU.

Referring now to Figs. 2 and 3, the slate B', segments SU, SD, shaft S, switch contact s^2 and lever 17 can readily be distinguished. The lever 17 is pivoted at 30 on bracket 31, which is adjustably mounted on a circular slotted ring 32, as by bolt 33 and nut 34. The preferred construction is that an insulating strip 35 will connect the stationary contact s^4 and its holder 37 with the socket 38 formed in bracket 31 carrying the brush b^1 , 19 being a spring for pressing the brushes b^1 , etc., against the periphery of segment SD or SU. Small screws 40 connect the insulating strip 35 with brush socket 38 and the socket 37 for contact s^4 . The wire 27 is fastened to socket 38 and wire 16 to socket 37, the current being carried from the movable contact 36 on lever 17 and spring 19 to socket 38, when 36 is closed on s^4 . It will be observed that contact 36 is adjustably mounted in lever 17, so that when screwed in or out it will change the position of the inner end 45 of lever 17. This end 45 of lever 17 carries a roller 46 which engages with a double beveled cam 47 adjustably mounted in a holder 48 bolted to slate B'. The cam 47 is held by set screw 49 and can be moved readily by set screw 50, so that by adjusting screw contact 36 on the end of lever 17 and adjusting cam F by set screw 50, the precise moment at which the contacts 36 and s^4 will open can be very accurately determined, thus determining the floor stop. This is in addition to the adjustment of the entire lever mechanism on ring 32 by bolt 33 and nut 34.

In practice, the general positions of the levers 17 for the various floors will be determined by properly positioning them on the ring, then the floor stops can be still more finely adjusted by setting the cam F by set screw 50. If necessary, contact 36 is also adjusted.

It will be seen that the spring 19 positively closes the circuit as soon as the cam 47 moves away from the roller 46, and the cam 47 positively holds the switch open sufficiently to prevent arcing across. It will be understood that these switches are similarly constructed for each floor, and successively operate as the cam 47 passes the various rollers 46, but only one of these switches will be alive, the one corresponding to the predestined floor stop.

From the foregoing description, it will be seen that a comparatively simple indicator mechanism is provided by this invention in which the stop switches can be mechanically opened to effect the stop, with an extreme degree of accuracy.

The use of large contacts is permitted so that the control circuits can be supplied from the motor circuits without danger of burning out, though it will be understood that the starting and maintaining circuits can be entirely distinct from the motor circuits without affecting the invention.

Various modifications and changes in details may be made without departing from the scope of the invention, it being understood that any number of floors can be employed, and by reason of moving the levers toward and from the plane of the indicator a very large number of stops can be provided for in a relatively small space, there being, furthermore, but one magnet for each floor in addition to the main switch up and down magnets. This permits a considerable simplicity of wiring as well as reduction in cost of installation and maintenance.

Having thus described my invention, I declare that what I claim as new and desire to secure by Letters Patent is:—

- 30 1. In an automatic elevator, the combination with reversible controlling means, of main up and down magnets for operating said means, an indicator movable synchronously with the car having separated up and down sides respectively connected to said up and down magnets, circuits corresponding to the several floors leading from said indicator, each circuit terminating in a brush bearing on said indicator, said brushes being transferred from one side of said indicator to the other as the car passes the corresponding floor, a normally closed switch in each circuit, a holding magnet corresponding to each floor circuit, means for selectively energizing one of said floor magnets to start the car, and means operated by said indicator for mechanically opening said switches to stop the car at the floor whose magnet was energized.
- 50 2. In an automatic elevator, the combination with reversible controlling means, of main up and down magnets for operating said means, an indicator movable synchronously with the car having up and down sides respectively connected to said up and down magnets, circuits corresponding to the several floors leading from said indicator, each circuit being transferred from one side of said indicator to the other as the car passes the corresponding floor, a holding magnet corresponding to each floor circuit, means for selectively energizing said floor magnets to start the car to a predetermined floor and maintaining a circuit through said indicator to said main and floor magnets, a

normally closed floor switch in each of said floor circuits adjacent said indicator, and means carried by the indicator for mechanically operating said switches whereby to stop the car when the predetermined floor circuit is opened by said indicator.

3. In an automatic elevator system, the combination with reversible controlling means, of up and down controlling magnets therefor, means for establishing a running circuit to one of said magnets, a plurality of circuit closers for said magnets corresponding to a plurality of floors, an indicator driven with the car and having an up and a down side respectively in circuit with said controlling magnets, floor circuits from said circuit closers to said indicator, said circuits being transferred from one side of said indicator to the other as the car passes the corresponding floor, a series of normally closed floor switches arranged to be mechanically opened as said circuits are transferred, and means between said up and down sides of said indicator for successively actuating said switches to stop the car when a live floor circuit is opened.

4. In an automatic elevator, an indicator comprising a reversible shaft, a pair of separated circular contact segments driven by said shaft, a cam between said contacts, and a series of switches arranged concentrically with said contact segments, each switch having a lever projecting into the path of said cam, said levers being successively actuated by the cam.

5. In an automatic elevator, an indicator comprising a reversible shaft, a pair of separated circular contact segments driven by said shaft, a cam between and moving with said contact segments, and a series of relatively fixed, normally closed switches arranged concentrically with said contact segments, each switch having a lever arm projecting into the path of said cam, said lever arms being successively actuated by the moving cam and being circularly adjustable relatively to said cam.

6. In an automatic elevator, a reversible rotatable shaft, a pair of separated circular contact segments mounted thereon and insulated therefrom, a cam carried by said shaft and disposed between said contact segments, and relatively stationary brackets carrying one or more contact brushes bearing on the periphery of said segments, and normally closed switches adapted to be controlled by said cam.

7. In an automatic elevator, a reversible rotatable shaft, a pair of separated circular contact segments mounted thereon and insulated therefrom, a cam carried by said shaft and disposed between said contact segments, and relatively stationary brackets carrying one or more contact brushes bearing on the periphery of said segments and normally closed switches adapted to be controlled by said cam.

- closed switches adapted to be controlled by said cam, said brackets being adjustably mounted to vary the time of opening of said switches by said cam.
5. 8. The combination with a reversibly driven cam, of a relatively stationary switch, a lever carrying a contact of said switch at one end, said cam engaging the other end of said lever to actuate said switch, said switch contact being adjustable on the lever to vary the time of engagement of the lever and the cam.
9. The combination with a reversibly driven cam, of a relatively stationary switch, 15 a lever carrying a contact of said switch at one end, said cam engaging the other end of said lever to actuate said switch, said switch contact being adjustable on the lever to vary the time of engagement of the lever and the cam, and said lever and switch being bodily adjustable relatively to the cam to further vary the time of engagement of said cam and lever.
10. The combination with a reversibly 25 driven cam, of a relatively stationary normally closed switch, comprising a lever carrying a contact of said switch at one end, said cam engaging the other end of said lever to actuate said switch, said switch contact being adjustable on the lever to vary the time of engagement of the lever and the
- cam, and said cam being adjustable toward and from said lever.
11. The combination with a reversibly driven cam, of a relatively stationary switch, 35 a lever carrying a contact of said switch at one end, said cam engaging the other end of said lever to actuate said switch, said switch contact being adjustable on the lever to time the engagement of the lever and the cam, a 40 contact segment moving with said cam, and a contact brush carried by the lever switch support co-operating with said contact segment.
12. An automatic elevator controller comprising a rotatable disk, separated direction contact segments carried thereby, a series of stationary brushes bearing on said segments, an arm carried by said disk projecting radially between said segments, a cam carried 50 by said arm, and a series of bell crank switch levers concentrically mounted around said disk, one arm of each of said switch levers being in the path of said cam so as to be successively actuated thereby.

In testimony whereof I affix my signature, in presence of two witnesses.

EDWARD L. DUNN.
